MARYLAND.

ANTICREEPER FOR RAILS.

1,183,531.

Specification of Letters Patent.

Patented May 16, 1916.

Application filed October 9, 1915. Serial No. 54,984.

To all whom it may concern:

Be it known that I, WILLIAM D. BUTLER, a citizen of the United States, residing at Woodbine, in the county of Howard and 5 State of Maryland, have invented certain new and useful Improvements in Anti-creepers for Rails, of which the following is a specification.

This invention relates to rail anchors de- 10 signed for preventing longitudinal movement or creeping of railway rails, and its object is to provide a strong and reliable device of this kind which will firmly grip the rail, and which is so secured that it is not 15 liable to be shaken or jarred loose.

The invention also has for its object to provide a rail anchor which can be easily applied, and which is simple in construction.

20 With the herein stated objects in view, the invention consists in a novel combination and arrangement of parts to be herein- after described and claimed, and in order that the same may be better understood, 25 reference is had to the accompanying drawing, forming a part of this specification.

In the drawing, Figure 1 is a plan view showing the application of the invention; Fig. 2 is a side elevation thereof, and Fig. 30 3 is a cross-section on the line 3—3 of Fig. 1.

Referring specifically to the drawing, 5 35 denotes a railway rail, and 6 one of the ties on which said rail is supported. The rail has the usual base flanges 7.

The anchoring device which is the sub- 40 ject matter of the present application for patent comprises a base member or plate 8 having at one end lateral extensions 9 terminating in jaws 10, and at the opposite end 45 a means for positively gripping and clamping the rail. The jaws 10 are shaped to overhang and engage the respective base flanges 7 of the rail 5, and they are diagonally opposite each other. When the 50 base member, as a whole, is canted or given a slight twist or rotary movement in one direction, the jaws will be forced firmly against the base flanges. The gripping means effects this canting or twist of the

base member.

The gripping and clamping means referred to comprises a double wedging cam clamping member consisting of a rotatable disk 11 which is adapted to have its edge

wedged against the edge of one of the rail 55 base flanges. The edge of the disk also has a shoulder 12 which overhangs the base flange and is inclined to form a cam. The disk is so positioned that its edge engages the rail base edge, and the shoulder comes 60 down on top thereof.

The disk 11 is pivoted eccentrically on a stud 13 rising from a lateral extension 14 at one end of the base member 8, said ex- 65 tension projecting outward from the rail base a sufficient distance so that the disk may engage the base flange as described.

When the disk 11 is turned to wedge 70 against the edge of the rail base flange 7, the base member 8 is canted sufficiently to 75 force the jaws 10 firmly against the respective base flanges, and at the same time the inclined shoulder 12 overhanging the base flange is wedged down on top thereof. The device is thus firmly held in rail gripping 75 position, and there is no danger of its being jarred or shaken loose.

The device will be so positioned beneath 80 the rail 5 that the part 14 abuts against the tie 6, and as the device is clamped in fixed 85 position of the rail, the tie serves as an abut- ment to hold the rail against a tendency to creep. On the bottom of the part 14 is a depending flange 15 adapted to be embedded in the ballast or road bed of the track. The flange extends transversely and thus assists 90 to anchor the base plate 8.

A means is also provided for locking the disk 11 and preventing the same from turn- 90 ing in a direction to release the rail, said means comprising a pivoted pawl 16 carried by the edge of the disk, and engageable with ratchet teeth 17 on the top of the part 14. The disk also has a hand lever 18 for fa- 95 cilitating its operation, said lever being piv- oted so that when it is not in use it may be swung down on top of the disk out of the way.

I claim:

1. A rail anchor comprising a base mem- 100 ber having rail gripping means, and a cam clamp carried by said member and having wedging surfaces engageable respectively with the edge of a rail base flange and the top of said flange.

2. A rail anchor comprising a base mem- 105 ber having rail gripping means and a tie- abutting part, and a cam clamp carried by

said member and having wedging surfaces engageable respectively with the edge of a rail base flange and the top of said flange.

3. A rail anchor comprising a base member having rail gripping means and a tie-abutting part provided with a depending ground-penetrating flange, and a cam clamp carried by said member and having wedging surfaces engageable respectively with the 10 edge of a rail base flange and the top of said flange.

4. A rail anchor comprising a base member having opposite rail gripping jaws, and a cam clamp carried by said member and 15 having a wedging surface engageable with the edge of a base flange of the rail to cant the base member in a direction to engage the jaws.

5. A rail anchor comprising a base member having opposite rail gripping jaws, and a cam clamp carried by said member and having a wedging surface engageable with the 20 edge of a base flange of the rail to cant the base member in a direction to engage the jaws, said clamp also having a wedging surface engageable with the top of said 25 flange.

6. A rail anchor comprising a base mem-

ber having opposite rail gripping jaws at one end, and a cam clamp carried by the other 30 end of said member and having a wedging surface engageable with the edge of a base flange of the rail to cant the base member in a direction to engage the jaws.

7. A rail anchor comprising a base member having opposite rail gripping jaws, a cam clamp carried by said member and having a wedging surface engageable with the 35 edge of a base flange of the rail to cant the base member in a direction to engage the 40 jaws, and means for locking the clamp.

8. A rail anchor comprising a base member having opposite rail gripping jaws, and an eccentrically mounted rotatable disk carried by said member and adapted to wedge 45 against the edge of a base flange of the rail, said disk also having a shoulder which overhangs the top of said flange and is inclined to wedge thereagainst.

In testimony whereof I affix my signature 50 in presence of two witnesses.

WILLIAM D. BUTLER.
